UNITED STATES PATENT OFFICE.

JAN WILHELM FINSTER, OF HOLYOKE, MASSACHUSETTS.

OIL-FEEDING APPARATUS.

1,335,676.

Specification of Letters Patent. Patented Mar. 30, 1920.

Application filed June 19, 1919. Serial No. 305,354.

To all whom it may concern:

Be it known that I, JAN WILHELM FINSTER, a citizen of Poland, residing at 359 Park street, Holyoke, county of Hampden, 5 and State of Massachusetts, have invented certain new and useful Improvements in Oil-Feeding Apparatus, of which the following is a specification.

This invention has for its object the provision of means for feeding oil to a burner or furnace and commingling steam, gases or air under pressure so as to produce a vapor of inflammable nature.

This object is attained by the novel construction and combination of parts herein-after described and shown in the accompanying drawings, forming a material part of this disclosure, and in which—

Figure 1 is a side elevational view showing an oil feeding apparatus made in accordance with the invention.

Fig. 2 is a longitudinal sectional view taken through the center of the same.

Fig. 3 is an end view looking from the handle.

Fig. 4 is a sectional view taken through the parts in detail and indicating their relative position.

Fig. 5 is a transverse sectional view taken 30 on line 5—5 of Fig. 2, and

Fig. 6 is a transverse sectional view taken 35 on line 6—6 of Fig. 2.

Referring to the drawings in detail, the numeral 10 indicates a cylindrical metallic 40 casing closed at its outer end 11, except for a screw-threaded central opening 12, while its opposite open end contains a screw thread 13, of larger diameter, the casing terminating in an octagonal flange 14.

Formed with one side of the casing 10 is an extension 15, containing an inlet opening 16, the extension having a screw-thread 17 on its exterior by which it may be connected with a supply source.

Engaged in the opening 12, is a packing 45 nut 18, having an octagon head 19 bored to receive a packing 20, the opening being screw-threaded at its upper end to receive a gland 21, terminating in a hexagon head 50 22, and suited to receive the valve stem 23, having a threaded portion 24, engageable with the screw-threads in the nut 18 and actuatable by a hand wheel 25, secured to the reduced upper stem 26, by the nut 27, while

on the lower end of the valve stem 23 is a 55 conical valve 28.

Another cylindrical casing 30 is provided with a flange 31, formed octagonally, corresponding to the flange 14, the same containing internal threads 32, while the other end 60 of the body 10 has external threads 33, suited to be received in the threads 34 formed in the large end 35, of a diffuser cap 36.

A hollow plug having screw threads, respectively 37 and 38, formed upon each side 65 of an octagonal extension 39, is adapted to engage with screw threads 13 and 32, holding the bodies 10 and 30 in rigid engagement, while the reduced end 40, of the hollow plug extends into the body 30, and terminates in a screw-threaded extension 41, to which is fitted a disk 42, containing a plurality of perforations 43, adjacent to which is a tube 44, also fitted to the thread 41, the same extending outward, coincident with 75 the outer end of the diffuser cap 36.

Extending out from the body 30, is a hollow extension 45, containing a central opening 46, having screw-threads 47, upon its exterior engageable with a supply source 80 by which steam, compressed air, or the like may be entered into the body 30, which upon striking the hollow plug 40, is diverted and caused to pass out through the perforations 43, where it is commingled 85 with the oil discharged from the end of the tube 44.

In operation, the oil and air stem inlets, respectively 15 and 45, having been properly connected with sources of supply, the oil entered under pressure, is caused to pass through the central passage 48 in the plug 40, at the upper end of which is a valve seat 49, controlled by the valve 28, and operated by the hand wheel 29 so as to permit 90 a proper amount of oil to enter and pass through the diffuser, where it is mingled with steam entering through the small openings 43, forming a burning mixture in condition to be directed into a furnace or 95 burner as desired.

Having thus described my invention what I claim as new and desire to secure by Letters Patent, is—

A means for regulating the supply of 100 oil and steam to burners comprising a sectional body, a threaded plug uniting the sections of said body, a threaded steam inlet

at one end and a threaded oil inlet at the other side of said plug, a reduced extension on said plug leading into one of said body sections, a perforated disk on said extension, 5 a diffuser on said extension adjacent to said disk, a valve seat at the end of said plug opposite to said extension, a conical valve adapted to engage said seat, a stem over

said valve, an elongated packing nut engaging a screw thread on said stem, a gland 10 in said nut and a hand wheel on said stem, substantially as described.

In testimony whereof I have affixed my signature.

JAN WILHELM FINSTER.
